Assistant Examiner — Melvin L Davis

(57) **CLAIM**

The ornamental design for an inflatable pool toy, as shown and described.

DESCRIPTION

FIG. 1 is a perspective view of an inflatable pool toy showing the new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front elevation view of the inflatable pool toy with a first set of exemplary balls in the holes; and,

FIG. 10 is another front elevation view of the inflatable pool toy with a second set of exemplary balls in the holes.

The broken lines of FIG. 9 and FIG. 10 depicting balls represent environmental structure that forms no part of the claimed design.

1 Claim, 10 Drawing Sheets
